UNITED STATES PATENT OFFICE.

JAMES T. HAYNES AND HERBERT B. WEBB, OF KEENES, ILLINOIS.

ROAD-GRADER.

No. 886,802.

Specification of Letters Patent.

Patented May 5, 1908.

Application filed January 4, 1908. Serial No. 409,308.

To all whom it may concern:

Be it known that we, JAMES T. HAYNES and HERBERT B. WEBB, citizens of the United States, residing at Keenes, in the county of Wayne and State of Illinois, have invented certain new and useful Improvements in Road-Graders; and we do hereby declare the following to be a full, clear, and exact description of the invention, such as will enable others skilled in the art to which it appertains to make and use the same.

Our invention relates to new and useful improvements in road graders and our object is to provide means for loosening the surface of the road-way and moving the same towards the center thereof.

A further object is to provide means for gradually inclining the surface of the road-way from the center to each side thereof.

A still further object is to provide means for increasing or decreasing the depth to which the surface of the road-way is loosened and a still further object is to provide means for increasing or decreasing the width of the grader and a still further object is to provide means for packing the surface of the road-way.

Other objects and advantages will be hereinafter referred to and more particularly pointed out in the claims.

In the accompanying drawings which are made a part of this application, Figure 1 is a top plan view of our improved grader. Fig. 2 is a sectional view as seen on line 2—2, Fig. 3 is a sectional view as seen on line 3—3, Fig. 1, and Fig. 4 is a detail elevation of the worm and gear employed for operating a winding drum used in connection with our improved grader.

Referring to the drawings in which similar reference numerals designate corresponding parts throughout the several views, 1 indicates the main frame, to the forward end of which is secured a cross head 2, to the outer ends of which are pivotally secured beams 3, said beams extending rearwardly from the cross head 2 and having pivotally secured to their rear ends, auxiliary frames 4. Depending from the frames 4, are shanks 5, to the lower ends of which are rotatably secured cutting disks 6, which disks are adapted to engage the surface of the road-way and loosen the same, and, by setting said disks at the proper angle, the soil so loosened will

be moved towards the center of the road-way.

The forward edges of the auxiliary frames 4 are provided with semi-circular plates 7, which plates are adapted to move below the beams 3 and are adjustably secured to said beams by introducing pins 8 through the beams and through openings 9 in the plates and, by providing a plurality of the openings in each of the plates, the auxiliary frames may be set at various angles to the longitudinal plane of the frame 1 and, in order to provide a slightly oval surface for the road-way, the shanks are slightly increased in length from the inner to the outer end of the auxiliary frames, this feature being best shown in Fig. 2 of the drawings. The rear ends of the beams 3 are suspended from a bar 10 by means of chains 11, the lower ends of said chains being secured to the beams, while the upper ends thereof are secured to rollers 12 on the bar 10, said rollers being adapted to travel on the upper edge of the bar. The bar 10 extends laterally through standards 13 on the frame 1, said standards being provided with suitable slots 14, through which said bar extends and, in order to support said bar and provide means for raising and lowering the auxiliary frames 4, a shaft 15 is extended vertically through a platform 16 carried by the frame 1 and is swivelly secured to the bar 10 at its longitudinal center and, by providing threads on the shaft 15 and extending the same through a threaded socket 17 in the platform 16, the rotating of said shaft will raise and lower the ends of the beams 3 and the auxiliary frames carried thereby, a hand wheel 18 being secured to the upper end of the shaft, whereby the shaft may be readily operated and, by this means it will be seen that the disks may be elevated entirely out of engagement with the surface of the road-way, if desired.

The beams 3 are adapted to be swung laterally away from the frame 1 to dispose the disks to the outer edge of the road-way or into the gutter and, in order to hold the beams at varying distances from the frame 1, we provide any suitable form of cables or chains 19, the outer ends of which are secured to the beams 3, while the inner ends thereof are secured to a winding drum 20, so that by rotating said drum in one direction, the beams will be left free to swing away

from the frames, but, when rotated in the opposite direction, the beams will be drawn towards the frame.

The upper end of the drum 20 is extended 3 through the platform 16 and is provided with a gear 21, with which meshes a worm 22 on a shaft 23, said shaft being preferably inclined and the rear end thereof brought into 10 juxtaposition to a seat 24 on the platform 16, whereby the hand wheel 25, on the rear end of the shaft 23, may be readily reached by the operator. The forward end of the shaft 23 is rotatably mounted in a bearing 26, while the rear end thereof is similarly 15 mounted in a standard 27 and, in order to prevent rotation of the drum, whereby the cables will become loosened and the beams 20 permitted to spread apart, a latch 28 is pivotally secured to the standard 27 and in position to engage a ratchet wheel 29 on the shaft 23.

In order to pack the surface of the roadway after the same has been loosened by the disks and moved to the highest part or center 25 of the road-way, rollers 30 are provided, which are preferably secured to the rear end of the frame 1 and the faces of said rollers are also preferably curved to conform to the curvature of the surface of the road-way and 30 it will be clearly understood that while we have shown but two of the rollers, any number of the same may be placed in position in the rear of the disks.

The grader is adapted to be propelled in any 35 suitable manner, but preferably by means of a traction engine or similar device and, when so propelled, the cross bar 2 is hitched to the engine and the grader caused to travel in the rear of the engine and, by suspending the 40 disks from the beams 3, the gutters alongside the road-way may be reached by the disks and, at the same time, retain the engine in the center of the road-way.

It will be further understood that where 45 the surface of the road-way is in a softened state, any suitable form of blade may be employed for moving the soil to the center of the road-way instead of the disks. It will likewise be seen that the disks may be reversed and used for ditching purposes, the 50 disks loosening the soil and moving it to each side of the path of the grader and, when the grader is so used, the rollers are to be dispensed with.

It will thus be seen that we have provided 55 a very efficient and economical form of grader and one wherein the loosened soil from the outer edges of the road-way may be readily moved to the center of the road-way 60 and thoroughly packed and it will likewise be seen that the surface of the road-way will be gradually curved from the center to the outer edges thereof. It will likewise be seen that the parts of the grader can be quickly 65 and easily operated to lift the disks from en-

gagement with the earth's surface, or the beams operated to move the disks towards or away from the frame.

What we claim is:

1. In a grader of the class described, the 70 combination with a frame, a cross head at one end of said frame and rollers at the opposite end of said frame; of rearwardly extending beams secured to said cross head, means to control the swinging movement of said beams, 75 auxiliary frames pivotally secured to said beams and disks carried by said auxiliary beams adapted to loosen the soil and move the same laterally.

2. In a grader of the class described, the 80 combination with a frame and a cross head at one end of said frame, of beams pivotally secured to said cross head, auxiliary frames pivotally secured to one end of said beams, means to adjust the angle of said auxiliary 85 frames, a supporting bar for said auxiliary frames and means carried by the auxiliary frames to engage the soil and move the same laterally.

3. In a grader of the class described, the 90 combination with a frame having a cross head at one end thereof; of a pair of beams pivoted at one end to the ends of the cross head, auxiliary frames pivotally secured to the opposite ends of the beams, means to adjust the 95 angle of the auxiliary frames, a supporting bar, means to movably attach the auxiliary frames to the bar and disks carried by said auxiliary frames.

4. In a grader of the class described, the 100 combination with a frame having a cross head at one end thereof; of a pair of beams pivotally secured at one end to the cross head, auxiliary frames pivotally secured to the opposite ends of the beams, disks on said auxiliary frames, means to adjust the angle of the auxiliary frames, a bar above said auxiliary frames, means to movably secure the frames to said bar, cables attached to said beams and means to wind said cables, whereby the cables will be lengthened and the beams swung away from the frame or the cables shortened and the beams moved toward the frame.

5. In a grader of the class described, the 110 combination with a frame; of a beam at each side of the frame, means to pivotally secure the beam to the frame, auxiliary frames carried by the opposite ends of the beams, means to adjust the angle of the auxiliary frames, 120 disks carried by said auxiliary frames at varying heights, and means to raise and lower said disks.

6. In a grader of the class described, the 125 combination with a frame; of beams pivotally secured to said frame, auxiliary frames pivotally secured to the beams, disks carried by said auxiliary frames, a drum carried by the frame, cables extending between said drum and the beams, means to rotate said 130

drum, whereby the cables will be wound onto or off of said drum and the beams moved towards or permitted to be moved away from the frame, supporting means for the 5 ends of said beams and the auxiliary frames carried thereby and means to raise and lower said auxiliary frames, whereby the disks may be moved into or out of engagement with the earth's surface.

In testimony whereof we have signed our 10 names to this specification in the presence of two subscribing witnesses.

JAMES T. HAYNES.
HERBERT B. WEBB.
